UNITED STATES PATENT OFFICE

2,524,430

LOCKING CLOSURE

Elizabeth E. Dixon, Madison, Wis.

Application March 2, 1948, Serial No. 12,530

1 Claim. (Cl. 220—55)

1

This invention relates to new and useful improvements in closures for receptacles such as garbage containers and the primary object of the present invention is to provide a closure embodying novel and improved means for lockably retaining the closure relative to the open end of a receptacle.

Another important object of the present invention is to provide a cover for garbage receptacles and the like which are provided with a beading at their open ends, including a pair of beading engaging members and novel and improved means for simultaneously actuating the beading engaging members into or out of locking engagement with the beading.

A further object of the present invention is to provide a locking closure for garbage receptacles and the like that is extremely small and compact in structure and which is conveniently applied to or removed from a receptacle in a simple manner.

A still further aim of the present invention is to provide a closure of the aforementioned character that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to the parts throughout, and in which:

Figure 1 is a fragmentary perspective view of a receptacle, and showing the present closure applied thereto in a locked position;

Figure 2 is a perspective view of the lever supporting plate used in conjunction with the present invention;

Figure 3 is a bottom plan view taken substantially on the direction of arrow numbered 3 in Figure 1, and with dotted lines showing the beading engaging members in an unlocked position;

Figure 4 is a longitudinal vertical sectional view of the present invention applied to a container and taken substantially on the plane of section line 4—4 of Figure 3, and;

Figure 5 is a vertical sectional view taken substantially on the plane of section line 5—5 of Figure 3.

Referring now to the drawings in detail, wherein for the purpose of illustration, there is disclosed a preferred embodiment of the present

2

invention, the numeral 10 represents a cylindrical container or receptacle of any suitable size which is formed with an upwardly turned annular beading 12 at its upper open end 14.

Frictionally embracing the outer periphery of the container 10 at the open end thereof, in the annular flanged portion 16 of a closure plate 18 the lower face of which frictionally engages the upper open end of the container. Rigidly secured by any suitable means to the lower face of the closure plate 18, is a multisided anchor plate 20 having diametrically opposite integral extensions 22 and 24 which are transversely slit adjacent their ends 26 and 28, as at 30 and 32 to facilitate the portions of the extensions 22 and 24 between the slits 30 and 32, and the anchor plate 18 to be turned inwardly toward each other to form opposed complementary, channeled guides 34 and 36.

Slidably mounted in the guides 34 and 36 is a pair of beading engaging members or locking plates 38 and 40 the forward edges 42 and 44 of which frictionally engage the beading 12 to prevent removal of the closure plate 18 from the container 10. Extending below the channeled guides 34 and 36, is a pair of connecting links 46 and 48 the outer ends 50 and 52 of which are connected to beading engaging members 38 and 40 by rivets or the like 54.

Frictionally engaging the outer face of the closure plate 18 is a support disc or plate 56 that closes the central openings 58 which are provided in the closure plate 18 and anchor plate 20. This support plate 56 is formed with a central slot 60 that engages a pair of straps 62 the ends 64 of which are angulated to fixedly engage the inner ends 66 of the connecting links 46 and 48 by the medium of rivets 68. Integrally formed with the straps 62, is a hand grip or lever 70 having rounded or looped end portions 72 and 74.

In practical use of the present closure, the longitudinal axis of the hand grip 70 aligns the longitudinal axis of the beading engaging members 38 and 40 when the edges 42 and 44 of the beading engaging members are in a frictionally locked position under the beading 12.

To remove or release the beading engaging members from a locked position, the hand grip 70 is rotated slightly, approximately 45° whereby the ends 64 of the straps 62 will rotate, actuating the links 46 and 48 to pull the beading engaging members simultaneously toward the center of the anchor plate 20. In this position, the closure 18 may be conveniently removed from the container 10.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A latch mechanism for receptacle closures, said latch mechanism comprising an elongated anchor member, pairs of guides integrally formed with said anchor member and disposed at the ends of said anchor member, a pair of diametrically opposed radially slideable locking plates received in said guides, a manually rotatable hand grip carried by said anchor member and disposed between said locking plates, a pair of links having inner and outer end portions, pivot pins securing the inner end portions of said links to said hand grip, and further pivot pins securing the outer end portions of said links to said locking members, said links being spaced beneath said guides, said

hand grip including a pair of U-shaped straps, each of said straps having a web portion and inner and outer leg portions, said anchor member having a central opening receiving the web portions of said straps, the inner leg portions of said straps being spaced below the anchor member and above the links, and a loop integrally formed with the outer leg portions of said straps, the inner leg portions of said straps being secured to the inner end portions of said links by the first mentioned pivot pins.

ELIZABETH E. DIXON.
